UNITED STATES PATENT OFFICE

IRVIN F. DITTMAR, OF WILLIAMSPORT, PENNSYLVANIA, ASSIGNOR TO THE CROMAR COMPANY, OF WILLIAMSPORT, PENNSYLVANIA, A CORPORATION OF PENNSYLVANIA

MACHINE FOR COATING STRIPS OF LUMBER

Application filed September 13, 1924. Serial No. 737,528.

This invention relates to a machine for coating strips of lumber adapted to be used in connection with strip coating machines and especially to means for tilting the strip after it has been discharged from the finishing machine to cause the strip to drop on the receiving table with its finished face on top, such as disclosed in the patent issued October 7, 1924, to Elmer C. Dittmar, No. 1,510,465, the object being to provide means for tilting the strip of material after it has had its face coated, so that the strip of material will be deposited on the receiving table with its coated face on top so as to prevent the marring of the finished face of the strip after it has passed through the machine.

Another and further object of the invention is to provide a device which is capable of being attached to any coating machine in which the strip of material passes through the same on edge so as to turn the strip after it has left the machine to bring the finished face on top as it is delivered onto the receiving table.

Another and further object of the invention is to provide a device which when attached to a machine of this character will eliminate wear on the end of the guide way for the strip so as to increase the life of the machine to eliminate waste.

Another and further object of the invention is to provide a coating machine wherein the strip is brushed so as to remove any foreign particles from the edge of the strip after it leaves the guideway.

Other and further objects and advantages of the invention will be hereinafter set forth and the novel features thereof defined by the appended claims.

In the drawings,

Figure 1 is a side elevation of a finishing machine showing the application of my improved construction of tilting device thereto;

Figure 2 is a side elevation of a tilting device;

Figure 3 is an end elevation;

Figure 4 is a vertical section through the supporting roll of the tilting device showing the manner of mounting the same;

Figure 5 is a detail section through a por-

tion of the oscillating shaft for supporting the tilting roll;

Figure 6 is a detail section of the backing up roll and support;

Figure 7 is a section through the tilting roll;

Figure 8 is an end elevation of a supporting post;

Figure 9 is a side elevation of the supporting post;

Figure 10 is a top plan view of a block for supporting the backing roll;

Figure 11 is a plan view of the supporting block;

Figure 12 is a detail side elevation of a portion of a finishing machine showing the application of a tilting device and cleaning brushes;

Figure 13 is an elevation of the same;

Figure 14 is a section through one of the brushes and support;

Figure 15 is a side elevation of a supporting post used in this particular construction of tilting device; and

Figure 16 is an end elevation of the same.

In the drawing 1 indicates a frame of a strip coating machine upon which is mounted a guide way 2 formed of tracks adjustably supported through which a strip of material to be finished is adapted to be forced by feed rollers 3.

Each roller is fixed on a shaft A journaled in an arm B pivotally mounted on a vertically disposed shaft C mounted in suitable bearings. The shaft C carries a gear D which meshes with a gear E fixed on the shaft A in order to rotate the feed roller when the shaft C is rotated. The shaft C has a depending lower end which carries a beveled gear F meshing with a beveled pinion G fixed on driven shaft H. The shaft H is provided with a pulley I over which passes a drive belt J carried by a pulley K fixed on a shaft L. The shaft L carries a pulley M over which passes a belt N driven by drive pulley N'. The shaft L has a pulley L' carrying a belt O which passes over a pulley P for driving the buffer 6.

The upper end of the shaft C carries a pulley Q over which passes a belt R for driv-

ing the pulley S carried by the upper end of the agitator shaft T disposed for agitating the material within the receptacle 5.

The strip is coated in its passage through the machine by coating receptacle 5 and is then burnished by a burnishing device 6, the succeeding strip serving the purpose to force out the preceding strip so that strips of material are fed continuously through the machine on edge and are finished in their passage therethrough, the above description being given so that the operation of my improved construction of tilting device when applied to a machine of this nature can be readily understood. It is, of course, understood that I do not wish to limit myself to the application of my improved construction of tilting device to any particular construction of coating machine as I am aware that with various changes, the tilting device can be applied to various forms of coating machines without departing from the spirit of my invention.

Secured to the frame 1 or bed of the machine at the delivery end of the machine is a post 7 on which the ends of the tracks forming the guide way are adjustably mounted as clearly shown. Carried by the post 7 is a block 8 provided with an eccentric pin 9, on which is mounted a backing up roll 10 adapted to engage the back of the strip in its passage through the machine, said roller being adjusted and set so as to engage the back of the strip as it passes through the guide way.

Secured to the post 7 is a block 11 provided with a slot in which is adjustably mounted a stud shaft 12 adjusted vertically by screw 13, the end of the stud shaft being provided with a head 14 over which is revolvably mounted a hub 15, said stud being provided with an oil passage 16 for feeding lubricant to the hub 15. Secured to the end of the hub is an idle roll 17, the periphery of which is preferably formed V-shaped in cross section and is adapted to fit within the V-groove of the strip of the material in its passage over the same.

In the embodiment of my invention as herein shown I have illustrated and described a tilting device, especially adapted to be used in connection with a finishing machine for coating a strip of flooring which has a V-shaped groove along one edge and a V-shaped tongue along the other edge and the cooperating parts are formed this shape so as to support the strip after it leaves the guide way. It is, of course, understood that I do not wish to limit myself to an idle supporting roll with any particular construction of periphery as the shape of the periphery will be changed to correspond to the edge of the strip of the material which it engages.

Secured to the opposite faces of the upper end of the post are bearing blocks 18 in which is mounted an oscillating shaft 19 locked in

position therein by key 20 for preventing endwise movement. The oscillating shaft is provided with a transverse bore 21 intersected by a threaded bore 22 in which is mounted a thumb screw 23 for the purpose hereinafter described.

Extending through the transverse bore 21 of the oscillating shaft 19 is a lever arm 24 which is engaged by the thumb screw 23 and locked in its adjusted position. The lever arm 24 carries a stud shaft 25 on which is revolvably mounted a tilting roll 26 which is held in its proper position by a handle 27 secured to the end of the stud shaft 25. The stud shaft 25 and lever arm 24 are provided with lubricating bores through which the bearing of the idle roll is lubricated and this roll is adapted to bear on the upper edge of the strip of material as shown in Figure 3 so as to tilt the strip on the supporting or idle roll 17, a vertical line drawn through the center of the idle roll forming a pivot upon which the strip tilts by the weight of the tilting roll 26 so as to cause the strip of material to be delivered on the receiving table with its coated face up, thereby preventing the finished face of the strip from being marred or injured in any way in being delivered from the machine.

The downward movement of the tilting roll is checked by an adjustable set screw 28 and this roll is set so that the periphery of the same is in a position to engage the upper edge of the strip without retarding the movement of the strip through the machine.

In order to provide means for keeping the face of the tilting roll clean, I secure to the lever arm 24 a post 29 on which is mounted a pivotal lever 30 carrying a scraper 31 which has a shearing action on the face of the tilting roll 26.

In the embodiment of my invention as shown in Figures 12 to 16 I secure to the bed of the machine a post 7' constructed to enable the placing of a pair of brushes 32 and 33 mounted as shown in Figures 13 and 14 and adapted to be driven by belts 34 and 35 from a driving shaft of the machine so that the edges of the strip will be cleaned before it reaches the tilting device, said brushes being adapted to rotate in the reverse direction to the movement of the strip.

The brush supports are mounted on bearings of the posts 36 and through the adjustable links 37 and 38 working through an angle plate 39 from the handle 40 in which the links 37 and 38 are threaded; they can be adjusted so as to compensate for the wear to set the brushes in the proper position to engage the edges of the strip of coated material in its passage through the machine. This provides means for setting the brushes properly and to take up wear so that the edges of the strip will be thoroughly cleaned.

Secured to the post 7' is a block 8' provid-

ed with an eccentric pin 9' on which is mounted a backing up roller 10' adapted to engage the back of the strip in its passage through the machine.

5 Fixed to the post 7' is a block 11' having a slot in which is adjustably mounted a stud shaft 12' held in its adjusted position by screw 13'. The end of the stud shaft is provided with a head 14' over which is revolvably mounted a hub 15'. Fixed on the end of the head is an idle roll 17' having a periphery corresponding to the shape of the lower edge of the material passing through the machine.

10 15 Mounted in the upper end of the post 7' is an oscillating shaft 19' locked in position by a key 20' for preventing endwise movement. The shaft 19' is provided with a transverse bore through which lever arm 24' extends carrying stud shaft 25' on which is mounted a tilting roll 26' and operates in substantially the same manner as described in the preferred form.

20 25 The operation and manner of mounting the tilting device is substantially the same as shown in the preferred embodiment of my invention with the exception of the different shaped post 7', which provides means for placing between the ends of the guideway and the rollers of the tilting device, brushes for cleaning the edges of the material.

30 35 As the construction of the various rollers of the tilting device as shown in Figure 13 is substantially the same as shown in Figures 2 and 3, the same has not been described in detail as the operation is identical and the strip of material in its passage through the machine pivots on the supporting roll and is 40 titled by the tilting roll so as to turn the strip over on its side with the finished face up.

45 In all of the embodiments of my invention as herein shown a tilting roll is carried by an oscillating shaft so that the weight of the roll bears on the edge of the strip of material in its passage through the machine and as the tilting roll is arranged at an angle, the pushing action of the roll has a tendency to tilt the strip on the pivot of the supporting 50 roll so as to cause the strip to drop face upward on the receiving table of the machine.

55 From the foregoing description it will be seen that I have provided a tilting device for a finishing machine wherein a pivotally supported roll is held into engagement with the upper edge of a strip of material by gravity so as to exert pressure on the edge of the strip as the same is released from the supporting means of the machine in order to turn the strip with its unfinished face downwardly as it drops upon the receiving table of the machine.

60 It also will be seen that I have provided 65 means for supporting the strip after it leaves

its guiding means so as to allow the strip to turn by the pressure of the tilting roller.

While I have shown certain details of construction and manner of mounting the tilting device on the finishing machine, it is, of course, understood that I do not wish to limit myself to these details of construction as they can be varied to suit the various makes of machines and therefore I reserve the right to make various changes.

70 75 While in the drawing and specification I have shown and described a tilting device especially adapted to be used in connection with a coating machine, it is, of course, understood that the tilting device can be used in connection with other machines, such as the Yates Miller, or any other machine where it is desired to have the strip delivered from the machine with one of its faces uppermost and therefore I do not wish to limit myself to the use of my improved construction of tilting device to any particular form of machine.

80 85 What I claim is:—

1. A machine for coating strips of lumber having means for guiding and moving a strip 90 on edge therethrough and a roller disposed at the delivery end of said machine for turning said strip as it is delivered therefrom.

95 2. The combination with a machine for finishing strips of lumber, of a roller disposed at the delivery end of said machine, said roller being arranged to bear on the strip as it is delivered therefrom to turn the strip with its finished face upward as it is delivered on the receiving table of the machine.

100 105 3. The combination with a machine for finishing strips of lumber having means for guiding and propelling the strip therethrough on edge, of a roller disposed beyond said guiding means for supporting the strip after it leaves said guiding means and a tilting roller disposed to engage the strip above said supporting roller for turning the strip as it is discharged from said machine.

110 115 4. A machine for coating strips of lumber having means for guiding a strip on edge, a supporting roller disposed beyond said guiding means, and a gravity tilting roller adapted to engage the upper ends of said strip for tilting said strip as it is discharged from said machine.

120 5. A device of the kind described comprising a supporting post having a supporting idle roller and a pivotally mounted tilting roller.

125 6. The combination with a machine for coating strips having means for guiding and propelling the strip on edge in its passage therethrough, of a supporting roller arranged beyond said guiding means and a tilting roller arranged above said supporting means adapted to engage the upper ends of the strip for turning said strip as it is discharged from said machine.

7. The combination with a machine of the 130

kind described, of a post secured to the base of the machine, a block carried by said post, a backing up roll carried by said block, a second block carried by said post, a supporting idle roller adjustably mounted in said block, bearings carried by the upper end of said post, an oscillating shaft mounted in said bearings, a lever arm adjustably mounted in said oscillating shaft and a tilting roller carried by said lever arm.

10. 8. The combination with a machine of the kind described, of a post secured to the base of the machine, a block carried by said post, a backing up roll carried by said block, a second block carried by said post, a supporting idle roller adjustably mounted in said block, bearings carried by the upper end of said post, an oscillating shaft mounted in said bearings, a lever arm adjustably mounted in said oscillating shaft, a tilting roller carried by said lever arm, and means for limiting the downward movement of said tilting roller.

9. The combination with a machine of the kind described having means for guiding and propelling the strip on edge in its passage therethrough, of a post carried by the base of the machine, a block carried by said post, an idle roller adjustably carried by said block, bearings carried by said post, an oscillating shaft mounted in said bearings, a lever arm carried by said oscillating shaft, a tilting roller carried by said lever arm and means for limiting the downward movement of said tilting roller.

10. A machine of the kind described having means for guiding and propelling the strip on edge in its passage therethrough, a post carried by said machine having a block, an idle roller carried by said block for supporting the strip after it leaves the guiding means and a revoluble roller carried by an oscillating shaft for engaging the upper edge of said strip.

45. 11. A machine of the kind described having a guide way and means for propelling the strip through said guide way, means for supporting the strip as it is discharged from said guide way and means for turning the strip so as to deposit the coated face of the strip uppermost on the receiving table of said machine.

55. 12. A machine of the kind described having means for propelling and guiding a strip on edge in its passage therethrough, of an idle roller having a peripheral edge corresponding to the edge of the strip for supporting said strip beyond said guiding means and a tilting roller arranged to engage the upper edge of the strip for turning the strip as it is discharged from said machine.

In testimony whereof I hereunto affix my signature.

IRVIN F. DITTMAR.
